CENTERING TOOL

Wadsworth S. Jock, Newald, Wis.

Application October 16, 1946, Serial No. 703,648

1 Claim. (Cl. 33—191)

1 My present invention relates to an improved centering tool or gauge for circular sizes and shapes of cylindrical stock, and designed for determining the center point of stock as well as for ascertaining and measuring the radius or diameter of the stock. The tool is of the well known Y-shape or straddle type adapted to be applied to the exterior circumferential surface and a transverse face at the end of the stock, and it is manually operated for gauging and centering the work and automatically retracted and reset for successive operations.

The primary object of the invention is the provision of a tool of this type that is composed of a minimum number of parts that may readily be assembled in compact arrangement to insure simplicity in construction and operation of the tool together with efficiency and accuracy in the performance of its functions.

The invention consists essentially in certain novel combinations involving a reciprocable gage-blade and a co-planar carrier and its gage-pin with intermediate rotary operating parts, and a punch or marker, as will be more fully described and claimed.

In the accompanying drawings, I have illustrated one complete example of the physical embodiment of the invention wherein the parts are combined and arranged in accord with one mode I have thus far devised for the practical application of the principles of my invention, but it will be understood that changes and alterations may be made in these exemplifying drawings and mechanical structures, within the scope of my claim, without departing from the principles of the invention.

Figure 1 is a face view of the tool applied to a solid cylindrical rod or bar, and projected for a centering operation;

Figure 2 is a side view of the device or tool of Figure 1;

Figure 3 is a side view of the tool, broken away, for convenience of illustration, and with the instrument in retracted position;

Figure 4 is a sectional detail view of the supporting parts of the tool, with the gage-blade or centering-blade removed;

Figure 5 is a detail view in side elevation, of the reciprocable gage-blade or centering-blade, also showing the relation thereto of the carrier and its gage-pin.

Figure 6 is a detail view in rear elevation of the gage-blade or centering-blade;

Figure 7 is an enlarged transverse sectional view at line 7—7 of Figure 2;

2 Figure 8 is a fragmentary detail view with parts in section showing particularly the means for releasing the punch or marker of the centering tool; and

6 Figure 9 is a detail view showing the spring detent and connections for the punch or marker.

In the embodiment of the invention shown in the drawings, the tool or instrument is of a generally Y-shape, including a tubular shank or handle 1 and an integral or rigidly attached yoke having outspreading or diverging arms 2 and 3 disposed at right angles, or perpendicular to each other, for frictional contact with the exterior cylindrical surface of the stock S as shown in Figure 1, and the arms 2 and 3 are provided with bracing or strengthening ears or wings 2a and 3a respectively which extend outwardly thereof at right angles thereto.

15 The tubular handle, which forms a housing for the operating parts of the instrument, is fashioned with a longitudinally extending slot 4, and a screw plug 5 is used to close the open end of the handle or shank.

20 For manually actuating the instrument in a centering operation, I employ a spring-retracted slide unit mounted on the slotted handle, which can be moved into and out of operative position as later described in this application.

25 The slide unit includes an exterior, longitudinally extending scale blade 6 having gradations on its exposed face, and on one edge, and a knob or finger-piece 7 is mounted at one end of the blade for pressure thereon of a finger or thumb in projecting the centering unit.

30 35 The blade 6 is provided with a rearwardly extending projection 7' and head 9 which support flanges 8 and 8a. The face of the flange 8 is provided with teeth to form a rack bar 8B, while the face of the flange 8A is smooth. The projection 7' engages in the slot 4 of the tubular handle or shank to guide the blade 6. The head 9 is bored or drilled transversely thereof to receive a punch-pin 10 which forms the centering pin for the gage.

40 45 50 55 The punch-pin 10 is disposed transversely of the operating blade or unit, and loosely mounted therein to plunger under spring pressure into the surface of the stock to make the center mark. For this purpose, the punch 10 (Fig. 9) is provided with end collars 11, with which the slotted end of a flat spring 12 is connected, the other end of the spring being fastened as by a screw to the outer face of the blade 6. Within the head 9, the punch 10 is fashioned with an annular groove 13 (Fig. 9). A longitudinally extending

detent 14, having a U-shaped or formed head 15 fits around the groove 13 to form a trigger or trip device, for freeing the punch 10, as will be described.

The detent or trip 14 is mounted within the flanges 8 and 8A of the blade 6, and it is pressed into detaining engagement with the punch 10 and by a spring 15' coiled about the detent 14 and contained within the collars 15" slidably supporting the detent 14 and anchored to the blade 6 (Fig. 5).

A pull-wire 16 is attached at one end to the detent 14. This wire extends downwardly between the flanges 8, 8A toward the handle or knob 7 and, by means of a screw eye 17 threaded into the rearwardly extending projection 7' of the blade, is anchored at the lower end thereof.

The reciprocating movement of the blade 6 is transmitted by rotary devices to a gage pin that is movable in a plane normal to the blade, and adapted to impinge against the exterior circumferential surface of the stock S, for co-action with the punch-pin for ascertaining the radius of the cylindrical stock, and to act as a stop for the projecting or centering movement of the centering-blade and punch.

The gage-pin is designated as 18, and it is slidably mounted in a second rack bar or carrier 19 that is reciprocated with a shorter movement than the centering blade by movement translated from the blade through the rotary devices.

The rotary transmitting device includes a large gear 20 and a smaller pinion 21. The gear and the pinion are mounted upon, or journaled on, a fixed stud shaft 22, which is supported in a housing 23 intermediate the tubular handle 1, and the diverging arms 2 and 3. A helical spring 24, is coiled about the shaft 22 with one end fixed to a removable plate 23A, secured to the housing 23 by a screw 23B, at 23' and its other end fixed to the gear 20 at 20'.

The spring 24, it will be apparent, is provided to retract the centering blade, and to afford a resilient resistance to the projecting movement of the blade; and the spring also performs the same functions in connection with the gauge pin 18 and its rack bar 19.

The rack bar 8B, which is attached to the blade 6, meshes with the large gear 20, and the gear 20 and pinion 21 are rotated by the rack bar 8B, so that the pinion 21, which meshes with the rack bar 19, causes reciprocation of this bar with its gage-pin or plunger 18.

Suitable slide bearings or guides 25 are provided within the tubular handle and the casing 23 for the rack bar 19, and openings 25' are provided in the handle for the rack bar 8B and the flange 8, for maintaining the rack bars in parallelism and in close contact with the gear and the pinion to insure accuracy in the movement of the parts and to assure efficiency in the operation of gaging and centering.

The punch 10 is automatically set or cocked, under action produced by the retracting movement of the centering blade 6, against tension of the spring 12, and this tension of the spring is ample, when the pin is released, to plunge the punch-pin against the face of the stock S to make a center mark.

For setting or cocking the punch a cam-lug 101 (Fig. 3) is mounted or fixed on a suitable part of the tool in the path of the pointed end of the punch 10 for frictional engagement therewith. As the projected punch contacts with and passes the cam lug 101, the punch-pin is forced

through the supporting head outwardly from the tool until the spring detent 14 automatically snaps into the annular groove 13 of the punch, thus setting the punch for a centering operation.

The punch is released by the withdrawal of the trip, trigger, or detent 14 under a pull or jerk on the wire 16, and the releasing movement is initiated by the gage-pin 18 as it strikes or encounters the circumferential face of the stock, together with relative movement of the rack bar 19 at the end of its operating stroke.

For this purpose a spring-lever 26, of the bell crank type, is pivoted at 27 on a bracket 28 fixed at an end of the rack bar 19. The short arm of the lever is fashioned with an eye, loop, or perforated lug 29 surrounding an adjusting nut 30 threaded on the protruding end of the gage-pin 18, and a similar perforated lug 31 of the long arm of the lever surrounds the wire 16.

When the upper end of the gage-pin 18 strikes the stock S a relative jerking movement from the rack bar 19 and the lever-supporting bracket 28, causes the long arm of the lever to swing away from the centering blade. This swinging action pulls on the wire 16, resulting in a pull that is imparted to the spring detent 14; the detent is thus withdrawn from the punch pin, and the released pin is projected by means of the spring 12 to mark the stock.

To facilitate operation of the lever 26 a spring 260 may be mounted on the bracket 28 to bear against the lever, there being an adjusting nut 30 mounted on the threaded end of the gage-pin.

If desired the instrument may be used for marking other than center marks on the stock, i. e., eccentrically located marks may be gaged or measured and indicated on the stock. For this purpose the blade is moved or projected the required distance and then fixed in its adjusted position by means of a set screw mounted in the blade to impinge against the shank of the tool. Then by applying the fixed instrument to the stock the measured distance may be indicated by the scale on the blade and the punch may be used to make the mark.

In both uses of the instrument, for centering or marking the center of the stock as well as for locating eccentric marks on the stock, the gradations of the scale on the operating blade are employed for measuring and gaging the radius of the cylindrical work-piece.

In Fig. 1 the tool or instrument is shown as applied to the stock S which is of approximately the largest size with which the illustrated tool may be used, and of course it will be understood that this size of tool may be used with smaller sizes of stock. The tool or instrument may be manufactured in various sizes, but the ratio between gears 20 and 21 is so chosen that the punch pin 10 is centered on the stock S simultaneously with the gage-pin 18 rotating bell crank 26 to pull wire 16 to release the pin 10 for striking movement by spring 12. Thus, the differential ratio

$$\left(\frac{\sqrt{2}}{\sqrt{2}-1} \right)$$

in speed and length of movement between the gage-blade and the carrier 19 with the gage-pin 18 is maintained, and these related parts are associated and operated so that distance, or a radius, may be gauged or measured between the contact end of the gage-pin 18 and the point of the punch.

Having thus fully described my invention, what I claim as new and desire to secure by Letters Patent is:

In a centering instrument, a housing, a manually reciprocable blade slidable in said housing, a head on said blade, a punch movably mounted transversely in the head, spring means mounted on the blade and attached to the punch for projecting same from the head, a spring actuated detent on said blade and locking the punch against movement by the spring means, a pull wire having one end connected to the detent and its other end anchored on the blade, a carrier, a gauge pin slidably mounted in said carrier, rack and gear means slidable in the housing and operative under movement of the blade in one direction to pull the wire to actuate the detent to release the punch for movement by the spring means, a means on the housing operative under movement of the blade in the opposite direction to coact with the punch for resetting the same against the spring means.
